(57) **CLAIM**

The ornamental design for an LED wall light, as shown and described.

DESCRIPTION

FIG. 1 is a perspective view of an LED wall light showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective view of the LED wall light of FIG. 1 as it would be positioned during use.

The broken lines depict portions of the LED wall light that form no part of the claimed design.
